UNITED STATES PATENT OFFICE.

JOHN KOHNER, OF LEWISTON, MINNESOTA.

ACETYLENE-GAS GENERATOR.

1,117,058.

Specification of Letters Patent. Patented Nov. 10, 1914.

Application filed November 8, 1913. Serial No. 799,920.

To all whom it may concern:

Be it known that I, JOHN KOHNER, a citizen of the United States, residing at Lewiston, in the county of Winona and State of Minnesota, have invented certain new and useful Improvements in Acetylene-Gas Generators, of which the following is a specification, reference being had therein to the accompanying drawing.

10 This invention relates to acetylene gas generators and has for its object the production of a simple and efficient means which will efficiently control the feeding of the carbid to the water containing compartments of the generator.

Another object of this invention is the production of a simple and efficient means for allowing the escapement of excess gas providing the gas chamber should be over-20 supplied with gas.

With these and other objects in view this invention consists of certain novel combinations, constructions, and arrangements of parts as will be hereinafter fully described 25 and claimed.

In the accompanying drawings:—Figure 1 is a vertical section of the generator. Fig. 2 is a section taken on line 2—2, of Fig. 1. Fig. 3 is a section taken on line 3—3, of Fig. 30 1 looking in the direction of the arrow. Fig. 4 is an enlarged vertical sectional view through the piston casing. Fig. 5 is an enlarged sectional view through the upper end of the piston casing showing the manner of 35 holding the piston rod in a set position. Fig. 6 is a perspective view of the upper end of the piston rod. Fig. 7 is a transverse sectional view taken on line 3—3, looking in the opposite direction to the arrow. Fig. 8 40 is a detail perspective of the closure valve for the lower end of the carbid receptacle.

The present device which is illustrated is especially adapted for use upon automobiles and other vehicles and is built especially to 45 prevent the splashing of liquid or water into the carbid receptacle so as to come in contact with the carbid contained in the upper tank. It should be understood, however, that the present device is adapted for use in 50 lighting houses and for other purposes and may be modified as to its detail mechanical construction without departing from the spirit of the invention.

55 Referring to the drawings it will be seen that 1 designates the base of the generator

which comprises a tank shape body having a flared bottom 2. This bottom 2 is provided at its lower end with a clean-out opening 3 to facilitate the cleaning of the bottom of the receptacle when it is so desired. The 60 base or water containing tank 1 is provided with a substantially inverted cone-shape hopper 4 which is open at its lower end as indicated at 5 and over this opening 5 is placed a substantially dome-shape shield 6, 65 which shield is supported above the inner face of the hopper 4 by means of upwardly extending legs 7 so as to allow the carbid to readily slide into the water or liquid contained in the bottom of the tank. The 70 liquid or water is adapted to be placed in the tank 1 at a sufficient height to extend slightly above the lower end of the hopper 4 and in view of the fact that the hopper 4 extends downwardly into the liquid within 75 the tank 1, it will be seen that this will prevent the splashing of the liquid in case the body of the generator should be subject to sudden jars as would be the case when used upon automobiles and other vehicles. Of 80 course, it should be understood that the water containing tank or base 1 may be provided with any suitable filling opening.

A carbid containing section or compartment 8 is detachably mounted upon the 85 upper end of the base 1 and is provided with a circumferential flange 9 upon its lower end to fit tightly around the upper edge of the base 1. A sealing washer 10 is interposed between the carbid containing 90 receptacle 8 and the base 1 so as to constitute an air, gas and water tight joint between the two sections. The carbid containing section 8 may be provided with any suitable 95 means such as illustrated at 11 for the purpose of allowing the device to be attached to any desired support such as a vehicle or automobile frame. The carbid containing section 8 is provided at its upper end with an upwardly extending collar 12 upon which 100 is threaded a removable cap 13 so as to normally close the upper end of the carbid containing section 8. This cap may, however, be removed when it is so desired.

A pressure gage 14 may be carried by the 105 carbid containing section 8 so as to indicate the amount of gas pressure within the base 1 if it should be so desired. A gas supply pipe 15 is connected to the carbid containing section 8 near the lower end thereof so 110

as to communicate with the base 1 to allow the passage of acetylene gas from the generator.

A carbid delivering hopper 16 is mounted 5 within the carbid containing section 8 and comprises a substantially inverted cone-shape body having an open lower end 17. A transversely extending guiding bar 18 is carried by the hopper 16 and this guiding bar 18 is provided with an eye 19 through which the vertically extending guiding rod 20 passes. This guiding rod 20 carries a helical twisted agitator bar 21 which bar 21 terminates in a valve 22 at 15 its lower end. This valve 22 has a depending pin 22', and this pin 22' is pivotally connected to the link 23 by means of a pivot pin 24 or may be connected in any desired manner without departing from the spirit 20 of the invention. The carbid is placed within the upper end of the carbid containing section 8 through the opening which is normally closed by means of the cap 13, and the carbid 25 is delivered from the hopper 16 through the opening 17 when the valve 22 is moved away from the opening 17 to the position shown in full lines. One end of the link 23 is pivotally connected to a supporting rod 25 which constitutes a suspending means therefor, and the opposite end of this link 23 is provided with a longitudinally extending slot 26 which slot receives a transversely extending pin 27 carried by the vertically extending piston rod 28. The piston rod 28 is in this manner securely held in engagement with the link 23 so as to facilitate the operation of the link 23 as will be hereinafter more fully described.

40 The carbid containing section 8 carries a piston cylinder 29 which piston cylinder has a cap 30 threaded upon its lower end. This cap 30 is provided with a plurality of perforations 31 to admit the gas from the base 1 into the lower end of the piston cylinder 29. The piston rod 28 passes through this cap 30 and is provided with a reduced upper end 32 which passes through the piston head 33. This piston head 33 is loosely mounted upon 45 the piston rod 28 and is normally forced into engagement with the beveled shoulder 34 of the piston rod by means of a tension spring 35. The tension of this spring 35 may be adjusted by means of a nut 36 which 50 is threaded upon the upper end of the piston rod 28. The piston head 33 may of course be formed of any desired construction for the purpose of performing the desired function. The lower end of the rod 28 is bifurcated 55 so as to straddle the link 23 similar to the manner in which the depending pin 22' straddles it as is illustrated in Fig. 8. A coil spring 37 is mounted upon the lower end of the piston rod 28 and is interposed between 60 the cap 30 and an adjusting nut 38, which ad-

justing nut 38 is threaded upon the lower end of the piston rod 28 for the purpose of regulating the tension of the spring 37.

The piston cylinder 29 and section 8 are provided with registering apertures 39 70 which registering apertures will allow the escapement of excess gas which has accumulated in the base 1.

The agitator bar 21 is provided with a toothed periphery 40, which will break up 75 the agglomerated lumps of carbid as the agitator bar passes through the carbid and in this manner cause only small particles of carbid to drop into the base 1, thereby allowing the acetylene gas to be more 30 quickly generated than if large particles of carbid were allowed to drop into the base 1.

From the foregoing description it will be seen that when the valve 22 is drawn 35 away from the opening 17 the carbid within the carbid containing section 8 will drop into the base 1 and by mixing with the water within the lower portion 2 of the base 1 will cause acetylene gas to be generated and 90 as the gas continues to be generated the piston head 33 will be forced upwardly thereby drawing the valve 22 to a closed position over the opening 17. In case the gas should continue to be generated at an 95 excess pressure the piston head 33 will be forced still farther upwardly against the tension of the spring 35 and cause the piston head 33 to pass beyond the apertures 39 thereby permitting the discharge of excess gas from 100 the generator. As soon as sufficient gas has escaped from the generator the piston head will assume its normal position and when sufficient gas has been used from the base 1, the piston will again drop in the piston cylinder 29 sufficient to cause the valve 22 to 105 be drawn away from the opening 17.

The piston rod 28 carries at its upper end an eye 41 which eye is adapted to receive the downwardly inclined end 42 of the locking rod 43. This locking rod 43 passes through a guiding sleeve 44 and carries a knob 45 at its outer end to facilitate the operation of the locking pin or rod 43. When it is desired to hold the valve 22 in a closed 110 position such as for instance when the carbid containing section 8 is being filled with the carbid the piston rod 28 is raised to the position shown in dotted lines in Fig. 1, and the downwardly extending end 42 of 115 the pin or bar 43 is forced through the eye 41 thereby holding the rod 28 in a set position and also holding the valve 22 in firm engagement with the edge of the aperture 17. Owing to the fact that the inner end 42 120 of the rod 43 is inclined downwardly it will be seen that the farther the pin or rod 43 is pushed inwardly, the rod 28 will be drawn 125 farther upwardly.

It, of course, should be understood that 130

when it is desired to fill the carbid receptacle 8, the cap 13 may be removed therefrom so as to allow the operator to place his hand into the carbid receptacle 8 and pull upwardly upon the rod 20 and in this manner raise the plunger 33 to such a position as to allow the locking rod 43 to engage the eye carried by the valve stem 28.

It will be seen that a very simple and efficient locking means for the piston rod 28 has been produced, whereby the valve 22 may be firmly held in a closed position.

Having thus described the invention what is claimed as new, is:—

1. A generator comprising a base, a carbid hopper carried thereby, said carbid hopper provided with a discharge opening, a link suspended within said base, a valve carried by said link, said discharge hopper provided with a discharge opening adapted to be closed by said valve, a piston cylinder supported adjacent said base and provided with means for admitting gas therein from said base, said cylinder provided with a gas discharge aperture for releasing excess pressure from said cylinder, a piston slidably mounted within said piston cylinder and provided with means connected to said link whereby said valve will be automatically opened and closed as said piston is moved longitudinally within said piston cylinder said piston adapted to control the discharge of gas through said aperture.

2. A generator comprising a base, a piston cylinder positioned adjacent said base, a carbid delivering hopper provided with a discharge opening, a valve, a link supported within said base and supporting said valve and adapted to normally open and close said opening in said carbid hopper as said link is raised and lowered, a piston rod connected to said link, a spring positioned upon the lower end of said rod for normally exerting a downward pressure upon said link, means for regulating the tension of said spring, a piston head slidably mounted upon said piston rod, a spring engaging the upper end of said piston, means for regulating the tension of said last mentioned spring, said piston cylinder provided with a gas discharge aperture for allowing the discharge of excess gas from said piston cylinder, and means formed upon said piston rod for limiting the downward movement of said piston head upon said piston rod.

3. A generator comprising a base, a piston cylinder positioned adjacent said base, a carbid delivering hopper provided with a

discharge opening, a valve, a link supported within said base and supporting said valve and adapted to normally open and close said opening in said carbid hopper as said link is raised and lowered, a piston rod connected to said link, a spring positioned upon the lower end of said rod for normally exerting a downward pressure upon said link, means for regulating the tension of said spring, a piston head slidably mounted upon said piston rod, a spring engaging the upper end of said piston, means for regulating the tension of said last mentioned spring, said piston cylinder provided with a gas discharge aperture for allowing the discharge of excess gas from said piston cylinder, means formed upon said piston rod for limiting the downward movement of said piston head upon said piston rod, an eye carried by said piston rod, and means engaging said eye for holding said piston rod against operation and also holding said valve in a closed position within said discharge aperture of said carbid hopper.

4. A generator comprising a base, a piston cylinder positioned adjacent said base, a carbid delivering hopper provided with a discharge opening, a valve, a link supported within said base and supporting said valve and adapted to normally open and close said opening in said carbid hopper as said link is raised and lowered, a piston rod connected to said link, a spring positioned upon the lower end of said rod for normally exerting a downward pressure upon said link, means for regulating the tension of said spring, a piston head slidably mounted upon said piston rod, a spring engaging the upper end of said piston, means for regulating the tension of said last mentioned spring, said piston cylinder provided with a gas discharge aperture for allowing the discharge of excess gas from said piston cylinder, means formed upon said piston rod for limiting the downward movement of said piston head upon said piston rod, an eye carried by said piston rod, a rod slidably mounted through said piston cylinder and provided with a downwardly inclined end passing through said eye and adapted to draw said piston rod upwardly as said last mentioned rod is moved into said piston cylinder.

In testimony whereof I hereunto affix my signature in presence of two witnesses.

JOHN KOHNER.
